UNITED STATES PATENT OFFICE.

EDWARD JOHN SCHOWALTER, OF RACINE, WISCONSIN.

TOY.

1,071,805.

Specification of Letters Patent.

Patented Sept. 2, 1913.

Application filed October 2, 1912. Serial No. 723,464.

To all whom it may concern:

Be it known that I, EDWARD J. SCHOWALTER, a citizen of the United States, and resident of Racine, in the county of Racine and State of Wisconsin, have invented certain new and useful Improvements in Toys; and I do hereby declare that the following is a full, clear, and exact description thereof.

My invention consists in what is herein particularly set forth with reference to the accompanying drawings and pointed out in the claims of this specification, its object being to provide simple, economical and pleasing toys, each comprising a stationary picture member, a superimposed movable picture member and means for manipulating the movable picture member to vary its position with respect to the stationary picture member so as to produce novel effects amusing or otherwise according to the picture as a whole.

Figure 1 of the drawings represents a front elevation of a toy in accordance with my invention partly broken away; Fig. 2, a rear elevation of the same having parts thereof broken away, and Fig. 3, a vertical section of the toy indicated by line 3—3 in Fig. 2. Referring by numerals to the drawings 4 indicates a card bearing a portion 5 of a picture that is either printed or applied on the card and is stationary. Another portion of the picture is likewise on a card 6 that may be cut upon outlines of said picture, as is herein shown, and the latter card 35 is movably superimposed upon the face of the one aforesaid.

A spacer 7, in the form of a disk or otherwise, is fastened by pasting or other suitable means upon the back of the card 6 and has 40 play in an opening 8 with which the card 4 is provided, the opening being circular, as shown, or of other suitable contour. The back of the spacer is suitably secured to a mover of any suitable form and material, 45 the one 9 herein shown being a strip of cardboard of gradually decreasing width in a downward direction and preferably provided with an outer stud 10 of sandpaper suitably secured thereto, abrasive side outer- 50 most.

As herein shown, the card 4 may be provided with a slit 11 in which to guide a portion 12 of the movable member of the picture, and it is also shown that said movable member of the picture may be attached 55 to another spacer 13 that has play in an

opening 14 in said card 4 and is connected to a stay-piece 15. This stay-piece laps the back of the card 4 and prevents the adjacent movable picture member from being 60 sprung outward from the plane of its movement.

A backing 16 is shown attached to the card 4 to conceal the greater portion of the mover 9 and stay-piece 15 in connection with 65 the spacers 7 and 13, respectively, an opening 17 being provided in the backing through which access is had to the stud 10 on said mover. Because of the position of the opening in the backing, the mover aforesaid cannot be sprung away from the adjacent card. By manipulation of the mover, 70 the movable portion of the picture may be reciprocated in a straight line and oscillated at any position of its vertical adjustment, 75 and these two movements may be combined at the pleasure of the operator.

In matters of detail the construction and arrangement of parts herein specified may be indefinitely varied without departure 80 from the scope of my invention as set forth in the claims herewith.

I claim:

1. A toy comprising a stationary picture member having a slit, a superimposed movable picture member having a portion thereof guided in said slit, a mover behind the stationary picture member, and means connecting the movable picture member and mover through a play opening provided in 85 the stationary picture member.

2. A toy comprising a stationary picture member, a superimposed movable picture member, a mover, means connecting the movable picture member and mover through 90 a play opening provided in the stationary member, and means preventing said movable picture member from being sprung away from said stationary picture member.

3. A toy comprising a stationary picture member having a play opening therein, a superimposed movable picture member, a mover, and a spacer in said opening connected to the movable picture member and the mover. 100

4. A toy comprising a stationary picture member having a play opening therein and a slit, a superimposed movable picture member having a portion thereof guided in said slit, a mover, and a spacer in said opening connected to the movable picture member and the mover. 110

5. A toy comprising a stationary picture member having play openings therein, a superimposed movable picture member, spacers attached to the movable picture member and engaging said openings, a mover in connection with one of the spacers, and a stay-piece in union with another of said spacers.

10 6. A toy comprising a stationary picture member, a superimposed movable picture member, a mover, means connecting the mover and movable picture member through an opening provided in the stationary pic-

ture member, and means preventing the mover from being sprung outward from the 15 plane of its movement.

In testimony that I claim the foregoing I have hereunto set my hand at the city of Racine in the county of Racine and State of Wisconsin in the presence of two wit- 20 nesses.

EDWARD JOHN SCHOWALTER.
